WRAPPING MACHINE

Rene J. Gaubert, Oakland, Calif.

Application July 2, 1934, Serial No. 733,393

15 Claims. (Cl. 93—2)

This invention relates generally to machines for wrapping various articles, as for example for applying "Cellophane" wrappers about cakes or boxes.

5 It is an object of the invention to provide a machine of the above character which will afford a relatively high capacity but which will be relatively compact as to size.

A further object of the invention is to provide 10 a machine which will not cause injury to readily crushable articles, and which therefore can be successfully employed in the wrapping of cakes or pies.

A further object of the invention is to provide 15 a machine which will take articles practically as fast as they can be supplied by an operator and which will deliver the articles completely wrapped. As will be presently made clear, the invention is characterized by the fact that 20 after inserting into the machine an article to be wrapped, various wrapping operations proceed while additional articles are being supplied.

Another object of the invention is to provide 25 a machine which can be readily adjusted to operate upon articles of a variety of sizes and shapes.

Further objects of the invention will appear 30 from the following description in which the preferred embodiment of the invention has been described with reference to the accompanying drawings.

Referring to the drawings:

Fig. 1 is a plan view showing a machine constructed in accordance with the present invention.

35 Fig. 2 is a side elevational view, partly in cross-section, illustrating the machine of Fig. 1.

Fig. 3 is a cross-sectional detail taken along the line 3—3 of Fig. 2.

40 Fig. 4 is a cross-sectional view taken along the line 4—4 of Fig. 2.

Fig. 5 is a detail illustrating the provision for securing an intermittent drive.

45 Fig. 6 is a cross-sectional view taken along the line 6—6 of Fig. 2.

Fig. 7 is a plan view, partly in cross-section, showing one of the wrapper-applying head assemblies.

50 Fig. 8 is a cross-sectional detail taken along the line 8—8 of Fig. 7.

My machine as illustrated in the drawings consists generally of a base structure 10 (Figs. 1 and 2), which serves to carry the operating parts of the machine. The operating parts consist mainly of a plurality of wrapper-applying head as-

semblies 11 which embrace the articles to be wrapped and which carry members for disposing each wrapper in its final desired position. In conjunction with the head assemblies 11, there are tables 12 for initially supporting the articles to be wrapped, and also elevating mechanisms 13 associated with the tables. The articles are introduced into the front of the machine on one of the tables 12 (see the table on the left-hand side of Fig. 1) and are automatically discharged 5 from the machine over the inclined conveyor 14. The source of power is an electric motor 16, or like motive device.

Before explaining the parts of my machine in greater detail, it may be explained that the motor 16 drives a single rotatable member, and this rotatable member transmits motion to other parts to secure the desired cycle of operation. The rotatable part is a hollow shaft 17, which surrounds an upright stationary shaft or standard 18. The lower end of standard 18 is fixed to the upper plate 19 of the base 10.

While the driving connection between the shaft 17 and the motor 16 may vary in construction, I have illustrated an electric motor 16 pro-

vided with a gear reduction box 21. Extending from the gear box there is a drive shaft 22 carrying the driving pinion 23. This pinion engages a gear 24 which is secured to the lower end of shaft 17. The electrical circuit to motor 16 is

such that the drive is intermittent; that is, so that when a switch is closed to energize the motor, the motor operates for a predetermined length of time to rotate shaft 17 a predetermined angular distance, after which the motor is automatically de-energized. A simple manner of ac-

complishing this result is to provide a motor switch in conjunction with certain of the parts driven by the motor, whereby the motor circuit is automatically opened after a predetermined angular rotation of shaft 17. Thus, referring to

Fig. 5, I have shown such an automatic switch associated with the pinion shaft 22. Pivotaly mounted adjacent this shaft there is a lever 25,

which is urged in one direction by the compression of spring 26. The free end of this lever car-

ries an electrical contact 27, co-operating with a stationary electrical contact 28. These contacts are connected in series with the electrical circuit

to the motor, and can be shunted out by a man-

ually-operated switch. Mounted upon the upper

50 end of shaft 22 there is a roller 29 which is eccentric with respect to the axis of rotation of shaft 22. As shaft 22 rotates, for each revolution roller 29 engages lever 25 and effects sufficient

movement to open the contacts 27 and 28. Preferably, the motor is provided with a magnetic brake to effect quick stopping when the energizing circuit is de-energized.

5 A suitable detailed construction for the head assemblies 11 can be best understood by reference to Figs. 7 and 8. As illustrated, each head assembly consists of an annular ring 32 secured to a projecting arm 33. The inner end of this arm 10 is fixed to a flange 34, which in turn is secured to the upper end of shaft 17. Overlying the ring 32, and secured thereto, there is a cover ring 36. For the purpose of affording an opening 40 through the head assembly, which will conform 15 substantially to the size and shape of the article being wrapped, I provide an article-receiving member 37 which is likewise annular in outer contour. Assuming that this member is made of sheet metal, as illustrated, its upper and outwardly extending flange 38 is removably secured to the cover ring 36 by means of lugs 39 and cap screw nuts 41. The inner depending flange portion 42 extends substantially the depth of the head and affords the opening 40 which is proportioned 20 in accordance with the size and shape of the article being wrapped.

At this point it may be explained that in wrapping an article, the wrapper is first laid across the top of the article, and then the article is 30 forced upwardly into a position within a head assembly, whereby the wrapper extends downwardly along the sides of the article. For the purpose of folding or positioning the depending edges of the wrapper laterally over the bottom of 35 the article, I provide movable folding members 44, 46 and 47. These members are formed of relatively thin sheet metal and underlie the other parts of the assembly. In order to carry the members 44 and 46 for sliding movements toward and away from each other, I provide a pair 40 of rods 49 and 51 which are substantially parallel and which are slidably mounted in opposite sides of the ring 32. One end portion 52 of member 44 is secured to the rod 49, while the end portion 45 53 of member 46 is secured to the rod 51. While the sliding movement of rods 49 and 51 is limited, sufficient movement is afforded so that members 44 and 46 can be retracted beyond the edges of opening 40, or can be moved together substantially 50 to the position illustrated in Fig. 7. The mounting just described preferably permits replacement of folding members 44 and 46, in accordance with the character of articles being wrapped.

The folding member 47, as illustrated, is also 55 formed of sheet metal, but instead of having its wrapper-engaging edge 56 straight, as in the case of members 44 and 46, this edge is cut to a substantially V contour. One corner portion 57 of this member is secured to a rod 58, which is disposed at right angles to the rods 49 and 51 and which is likewise slidably carried by the ring 32. Rod 58 is permitted sufficient sliding movement 60 so that member 47 can be slid either to substantially the position shown in Fig. 7 or to a retracted position beyond one side of opening 40.

In order to more adequately support the members 44, 46 and 47, there is a relatively flat ring 59 underlying the assembly, which is spaced with respect to the lower face of ring 32 and secured 70 thereto by screws 60. The free ends 61 and 62 of members 44 and 46 project into the space thus afforded, so that these members are in part supported by the ring 59. A guide groove 64 is also formed on ring 59, to receive the free edge portion 75 66 of member 47.

As a part of actuating means for the members 44, 46 and 47, I provide two relatively rotatable rings 68 and 69 which are loosely assembled upon the ring 32 immediately below the cover ring 36. Ring 68 is provided with a pair of lugs 71 which in turn are provided with slots 72 to receive pins 73. Pins 73 are in turn fixed to the rods 49 and 51. Likewise mounted upon and projecting from ring 68 is a finger 74, by means of which the ring 68 may be rotated in one direction (clockwise as viewed in Fig. 7) to effect closing movement of folding members 44 and 46. Ring 69 is likewise provided with a slotted lug 76 which engages pin 77. This pin is secured to rod 58, whereby when ring 69 is rotated, sliding movement is afforded to rod 58, to effect movement of the folding member 47. Ring 69 also carries a projecting finger 78.

At this point it may be briefly explained that when the head assembly is swung through a circular path, fingers 74 and 78 are engaged and moved by trip members, to effect closing movement of the folding members. To provide for opening movement of the folding members, rings 68 and 69 are also provided with projecting fingers 79 and 81 respectively. These fingers are likewise adapted to successively engage a trip member, to effect rotation of rings 68 and 69 in a direction to effect retraction of the folding members.

Positions of fingers 74 and 78 (relative to the head assembly) corresponding to open position of folding members 44 and 46, are indicated at 30 74a and 78a. The corresponding positions of fingers 79 and 81 are indicated at 79a and 81a.

The trip means for co-operating with the head assemblies can be constructed as follows:—The top casting 19 of the base 10 is provided with a lateral projection 83, which carries the lower end of an upright standard 84. The upper end of 40 this standard carries a bracket 86 which serves as a mounting for a plurality of adjustable trip members 87, 88 and 89. These trip members serve to successively engage and actuate the fingers 74 and 78, in a manner to be presently explained. Secured to the upper end of standard 17 there is also a laterally extending arm 91, the outer end of which carries a roller 92 (Fig. 1). This roller is interposed in the path of movement of the fingers 79 and 81.

The particular form of table 12 employed, for supporting the article to be wrapped preliminary to transposing the article into one of the head assemblies 11, consists of a flat-topped casting 96 carried by a bracket 97 which in turn is formed 55 upon the shaft 17. In order to properly center the article to be wrapped, each casting 96 is provided with slots 98 adapted to accommodate adjustable blocks 99.

The elevating means associated with each table 60 consists of a rod or plunger 101 which is slidably carried by the corresponding casting 99. Each plunger 101 is aligned with a corresponding overlying head assembly 11, and a plate 102 secured to its upper end serves to provide an adequate 65 supporting area for the article.

In order to secure the desired cyclic lifting and lowering movements of plunger 101, I preferably provide cam means constructed as follows. Radially extending brackets 103 are carried by shaft 70 17 (Fig. 2) and form fulcrum supports for the L-levers 104. Mounted upon the fixed gear train housing 106 there is a cam 107 having a contour substantially as shown in Fig. 4. Preferably a certain amount of accurate adjustment is afford- 75

ed for this cam, for example, by securing it to the gear housing 106 with screws 108 engaging through slots 109. The inner depending arm of each L-lever 104 is provided with a spherical surface roller 111, serving to engage the surface of cam 107. The outwardly extending arm 112 of each L-lever extends through a slot formed in the lower portion of the corresponding plunger 101. In order to minimize friction, rollers 113 are provided above and below the arm 112. It is evident that with the arrangement just described, particularly with the cam having a contour such as shown in Fig. 4, as each table 12 makes one complete revolution about the standard 18, each plunger 101 is raised to an elevated position to transpose an article into the overlying head assembly 11, after which it is lowered back to its initial position.

In Fig. 2, an article 116 to be wrapped has been indicated in dotted lines, as it is introduced into the machine by an operator. Overlying this article a wrapper 117 is also indicated, such as a sheet of "Cellophane." In introducing such a wrapper it is desirable to provide gauge and retaining means so that the wrapper is properly centered and retained upon the article until engaged by a head assembly. The gauge means in this instance consists of a pair of members 118, each carrying rollers 119 and 119a to receive the edge of the wrapper. The uppermost rollers 119a are loosely mounted so that when the edge of a wrapper is thrust between the upper and lower rollers, a light grip is afforded. Members 118 are pivotally carried by the ends of links 121 which in turn are pivotally carried by a collar 122. Extending between the two members 118 there is a spacer bar 123 which, by the manipulation of a wing nut 124, may be employed to determine the distance between the members 118, in accordance with the width of the wrapper being employed.

Collar 122, instead of rotating in unison with the head assemblies, is journaled to the upper portion of shaft 17. By means of a tension spring 126, the collar 122 and the parts carried by the same are urged in a counterclockwise direction, as viewed in Fig. 6, to normally assume a position at the front of the machine. Interposed between the collar 122 and the shaft 17, I provide a releasable drive means whereby, when shaft 17 is rotated, collar 122 is carried with it for a certain angular distance, after which it is released and permitted to return to an initial position under the urge of spring 126. Thus, shaft 17 (Fig. 2) is provided with a plurality of circumferentially spaced apertures 127 which serve to receive balls 128. A set screw 129 is fitted in collar 122, and its inner end is adapted to engage balls 128. The stationary standard 18 is provided with a flattened place 131 whereby a ball passing over the same is permitted to move inwardly. The operation of this mechanism is briefly as follows:— Assuming that shaft 17 is rotated in a clockwise direction as viewed in Fig. 3, the left-hand ball 128 first engages the inner end of set screw 129 whereby collar 122 and the elements supported by the same are likewise rotated. When the ball engaged by the inner end of the set screw passes upon the flattened place 131, it moves inwardly sufficiently far to disengage itself from the set screw 129, thus permitting the collar 122 to return to its initial position under the urge of spring 126.

At a proper point in the sequence of operations of the machine, it is desirable to transfer the article being wrapped to a shelf or supporting plat-

form which in turn leads to the discharge conveyor 14. For this purpose I have shown an arcuate shaped shelf or platform 133 (Figs. 1 and 6) which is disposed at a level immediately below the level of the head assembly 11 (Fig. 2). This shelf can be supported by suitable means, such as standards 134, which in turn are carried by the top casting 19 of base 10. The entrant end of shelf 133—that is, the end which first passes beneath the article being wrapped—is preferably cut to a V-shaped contour, as indicated at 136 in Fig. 1. A portion of shelf 133, namely, that section indicated at 137, is preferably electrically heated, to effect sealing of the folded portions of the wrapper. Overlying the heated section 137 I preferably provide a presser roller 138, made of some suitable resilient material such as soft rubber. This roller is shown journaled upon the end of an arm 139 which in turn is adjustably secured to the upper end of standard 18.

As has been previously mentioned, that part of the machine appearing in the left-hand portions of Figs. 1 and 2, is the front of the machine into which articles are introduced by the operator. To facilitate the picking-up of wrappers by the operator, a sheet rack 141 is provided which has its forward end curved upwardly.

Operation of the machine can now be reviewed as follows:—Assuming that the machine has been properly adjusted, the operator introduces the article 116 to be wrapped, upon the front table 12. At that time the plunger 101 of this table will be in a lowered position. The operator then places a wrapper, such as a sheet of "Cellophane", over the article substantially as indicated in Fig. 2, and during this operation elements 118 are utilized to ensure proper centering. The operator then closes a switch to start motor 16 in operation. The head assemblies 11, and also the tables 12, now rotate in unison, and during the initial part of such rotation the plunger 101 underlying the article is elevated to transpose the article into the overlying head assembly. Such transposition bends the wrapper down along the sides of the article in proper position to be properly folded inwardly. Immediately after the plunger 101 has reached the upper limit of its movement, trip member 89 engages finger 74 to cause a limited amount of angular rotation of ring 68. Such rotation causes folding members 44 and 46 to be moved inwardly toward each other and beneath the bottom of the article, although not to the full limit as shown in Fig. 7. The plunger 101 which up to this time has been supporting the article, is now dropped, whereby the article rests upon the folding members 44 and 46. Thereafter, finger 74 engages trip member 88, to effect a further angular movement of ring 68 and thus effect substantially complete closing of the folding members 44 and 46. About the time this operation is completed, finger 78 is engaged by trip member 87, to effect an angular movement of ring 69 to move the folding member 47 inwardly to the position shown in Fig. 1. Likewise, as the folding member 47 is moving (relative to the head) to its inward position, the head is progressing over the entrant end of shelf 133, so that this end of the shelf likewise co-operates with the folding member 47 to effect a final and complete folding of the wrapper.

When the above operations have occurred and the head carrying the article has moved substantially one-third of a revolution (120°), the motor circuit is automatically disrupted, where-

by the head assemblies come to rest substantially in the position shown in Fig. 1. Another head assembly and supporting table 12 are now before the operator, for receiving a succeeding article.

5 Tracing the first article through the complete cycle of operation, when the operator again initiates operation of the motor, the head assembly carrying the first article moves through a position wherein the fingers 79 and 81 are engaged 10 and actuated by roller 92, to retract all of the folding members 44, 46 and 47. The article is now adequately supported by the shelf 133, over which it slides until the head assembly again comes to rest substantially 240° from its initial 15 starting position. In such position of the head assembly corresponding to the lower right-hand position of Fig. 1, the article is being pressed down upon the heated section 137 by the roller 138. Assuming that a self-sealing type of "Cello- 20 phane" wrapper is employed, the folds of the wrapper are thereby heated and sealed together. While the wrapper is in such position, the operator is again introducing an article into the next head assembly, which is now at the front 25 of the machine. When the operator again closes the motor circuit, the head assembly, as illustrated in the lower right-hand part of Fig. 1, swings back to the front of the machine, and the wrapped article drops down through the assembly upon the inclined conveyor 14.

It will be evident from the above that my machine has many desirable characteristics. Although it occupies a relatively small space, it has a high capacity because it will take articles practically as fast as supplied by an operator. Since 35 no parts press tightly against the article during the wrapping operation, and since the articles are not inverted, no injury will be caused to readily crushable articles such as cakes. A relatively small amount of power is required for operation of the machine, and the drive is relatively simple in character, with all parts driven from a single motor. The machine is also flexible in its application to articles of different sizes 40 and shapes. If it is desired to re-adjust the machine for taking an article of a different size, the members 37 are replaced with members having different sized openings 40. For round articles the opening 40 is circular, as illustrated in the 45 drawings, but for articles of other shapes the opening 40 can be otherwise contoured, as for example rectangular or square. In setting up the machine for different types of articles, the lugs 99 on tables 12 are of course adjusted, so that 50 upon introducing the article upon a table it is properly centered with respect to the overhead assembly. Likewise, the gauging elements 118 are adjusted so that the wrapper can be quickly 55 introduced by the operator in a proper centered position.

I claim:

1. In a wrapping machine, an upright standard, a wrapper-applying head assembly serving to embrace an article to be wrapped, means extending laterally from the standard serving to rotatably support the assembly for rotation about the standard, said assembly including movable wrapper-folding members, means co-operating 65 with the assembly for transposing into the assembly an article to be wrapped, said last means being likewise carried by the standard below the head assembly and rotatable together with said assembly, and means including stationary trip fingers for actuating said folding members of

the assembly during rotation of the assembly about the standard.

2. In a wrapping machine, an upright standard, a wrapper-applying head assembly serving to embrace an article to be wrapped, means extending laterally from the standard serving to rotatably support the assembly for rotation about the standard, an article-supporting table disposed below the assembly and being likewise supported by the standard for rotation together with the assembly, elevating means carried by the table for transposing an article into said assembly, and means actuated by rotation of the assembly and the table about said standard for actuating said elevated means. 15

3. In a wrapping machine, an upright standard, a wrapper-applying head assembly adapted to receive an article to be wrapped, means extending laterally from the standard serving to support the assembly for rotation about the standard, a table disposed below the assembly and likewise carried by the standard for rotation together with the assembly, article-elevating means associated with the table for elevating an article into the assembly, drive means for effecting rotation of the assembly together with the table and the elevating means about said standard, and cam means for effecting operation of said elevating means in response to such rotation. 20

4. In a wrapping machine, an upright standard, a wrapper-applying head assembly carried by the standard for rotation about the same, said assembly in its rotation moving from a position in which an article is presented to the same, 35 about the arc of a circle back to said position, article-elevating means disposed below said assembly for lifting into the same an article to be wrapped, said elevating means being likewise rotatable about said standard together with the assembly, and means forming a receiving shelf for the article and adapted to underlie said assembly for a portion of its circular movement, the cycle of operation being such that the elevating means first lifts the article into the assembly as 40 the assembly moves from the position of presentation, then the edges of the wrapper are folded beneath the article, then the article is transposed upon the receiving shelf, and finally the assembly is returned to the initial position. 50

5. In a wrapping machine, an upright standard, a plurality of wrapper-applying head assemblies carried by said standard and adapted to rotate as a group about the same, said head assemblies being aligned with radii disposed 55 equal angular distances apart, drive means for effecting rotation of the assemblies about the standard, means for arresting the rotating movement of the assemblies after an angular movement equal to the angular spacing between said radii, a wrapper gauge carried by the standard at an elevation below said head assemblies, and means for causing oscillatory movement of said wrapper gauge in response to continual intermittent rotation of the head assemblies, the extent 60 of such oscillatory movement being substantially equal to the angular spacing between said radii. 65

6. In a wrapping machine, a head assembly serving to receive an article to be wrapped, said assembly including wrapper folding members adapted to be projected beneath the article, rings for effecting projection and retraction of the folding members, means for bodily swinging the head assembly in an arc of a circle, and trip 70 75

members relatively stationary with respect to the head assembly for effecting selective operation of the rings.

7. In a wrapping machine, an upright standard, a wrapper applying head assembly carried by the standard for rotation about the same, said assembly including movable wrapper-folding members, said assembly in its rotation moving from a position in which an article is presented to the same, about the arc of a circle back to said position, article-elevating means disposed below said assembly for lifting into the same an article to be wrapped, said elevating means being likewise rotatable about said standard together with the assembly, means forming a receiving shelf for the article and adapted to underlie the assembly for a portion of its circular movement, and means including stationary trip members for effecting selective operation of said folding members.

8. In a wrapping machine, an upright standard, a wrapper-applying head assembly serving to embrace an article to be wrapped, means extending laterally from the standard serving to rotatably support the assembly for rotation about the standard, said assembly including wrapper-folding members, trip means for actuating said folding members during rotation of the assembly about the standard, and stationary supplemental wrapper-folding means disposed to underlie the path of movement of the assembly.

9. In a wrapping machine, an upright standard, a plurality of wrapper-applying head assemblies carried by said standard and adapted to rotate as a group about the same, said heads being aligned with radii disposed equal angular distances apart, drive means for effecting rotation of the assemblies about the standard, means for arresting rotating movement of the assemblies after an angular movement equal to the angular spacing between said radii, said assemblies including movable wrapper-applying members, means serving to actuate said wrapper-applying members during rotation of the assemblies, and a supplemental stationary wrapper-folding means adapted to co-operate with all said assemblies.

10. In a wrapping machine, an upright standard, a plurality of wrapper-applying head assemblies carried by said standard and adapted to rotate as a group about the same, said assemblies being aligned with radii disposed equal angular distances apart, wrapper-folding elements carried by the assemblies, elevating means disposed below said head assemblies and adapted to elevate articles into the same, means for effecting rotation of the assemblies about the standard, means for arresting rotating movement of the assemblies after an angular movement equal to the angular spacing between said radii, means for actuating said elevating means during said rotation, and means including stationary trip fingers for effecting operation of the folding elements of all said assemblies during rotation of the same.

11. In a wrapping machine, a head assembly serving to receive an article to be wrapped, means for progressing the assembly through a cycle of movement from a position in which it receives an article to be wrapped and then back to such position, said assembly including wrapper-folding means adapted to be projected beneath said article, an article-receiving shelf disposed to under-

lie said assembly for only a portion of its movement, an inclined conveyor communicating with one end of said shelf for discharging articles from said head assembly, means for actuating said wrapper-folding means to project the same beneath said article before said article is positioned to overlie said shelf, and means for retracting said wrapper-folding means while said assembly overlies said shelf.

12. In a wrapping machine, a head assembly serving to receive an article to be wrapped with a wrapper disposed over the article, drive means serving to swing the assembly through substantially a horizontal plane and in an arc of a circle from a position in which it receives an article to be wrapped and then back to such position, said assembly including wrapper-folding means actuated during the course of such swinging movement, said wrapper folding means serving to fold edge portions of the wrapper beneath the article, and leaving a portion of the wrapper unfolded on one side of the article, and an article-receiving shelf disposed to overlie said assembly for only a portion of its circular movement, one edge of said shelf forming means for folding said portion of the wrapper beneath the article.

13. In a wrapping machine, a wrapper-applying head assembly serving to receive an article to be wrapped with a wrapper disposed over the article, means for transposing upwardly into said assembly an article to be wrapped, means for progressing the assembly together with said transposing means through a cycle of movement from a position in which an article can be presented to said transposing means and then back to such position, said assembly including wrapper-folding means actuated during the course of said movement for folding edge portions of the wrapper beneath the article, said folding means leaving a portion of the wrapper unfolded on one side of the article, an article-receiving shelf disposed to underlie said assembly for only a portion of its circular movement, one edge portion of said shelf forming means for folding said portion of the wrapper beneath the article, and means for lowering the article from said assembly and from one end of said shelf.

14. In a wrapping machine, a wrapper-applying head assembly serving to receive an article to be wrapped with a wrapper disposed over the article, means serving to transpose an article to be wrapped into a position within said assembly, a standard serving to support both said assembly and said means, said standard having an axis offset with respect to the assembly, drive means serving to swing the assembly together with said transposing means about the axis of said shaft, said assembly including wrapper-folding means actuated during the course of its movement about the axis of said standard for folding the wrapper beneath the article, said folding means leaving a portion of the wrapper unfolded on one side of the article, and a stationary article-supporting shelf adapted to receive the article after wrapping of the same, one edge of said shelf forming supplemental wrapper-folding means for folding said portion of the wrapper beneath the article.

15. In a wrapping machine, a head assembly serving to receive an article to be wrapped, means for progressing the assembly through a cycle of movement from a position in which it receives an article to be wrapped and then back to such po-

sition, said assembly including wrapper-folding means adapted to be projected beneath said article, an article-receiving shelf disposed to underlie said assembly for only a portion of its movement, an inclined conveyor communicating with one end of said shelf for discharging articles from said head assembly, means for actuating

said wrapper-folding means to project the same beneath said article before said article is positioned to overlie said shelf, and means for retracting said wrapper-folding means while said assembly overlies said shelf, a portion of said shelf being heated to effect a sealing operation.

RENE J. GAUBERT.
